UNITED STATES PATENT OFFICE.

GEORGE H. REITH AND HARRY F. ANDERSON, OF MARION, INDIANA; SAID REITH
ASSIGNOR TO JAMES BOYCE, OF CHICAGO, ILLINOIS.

SIGN-LETTER HOLDER.

1,116,628.

Specification of Letters Patent.

Patented Nov. 10, 1914.

Application filed July 17, 1913. Serial No. 779,646.

To all whom it may concern:

Be it known that we, GEORGE H. REITH and HARRY F. ANDERSON, citizens of the United States, residing at Marion, in the county of Grant and State of Indiana, have invented certain new and useful Improvements in Sign-Letter Holders; and we do declare the following to be a full, clear, and exact description of the invention, such as will enable others skilled in the art to which it appertains, to make and use the same.

This invention relates primarily to signs of that character known as illuminated lamp boxes, but more especially to the pane 15 fasteners which are employed in such boxes for holding the glass letters or the panels in place.

The object of the invention is to improve the construction of the holder whereby the 20 least possible portion of the panel is covered so that if it be glass the greatest amount of light may shine therethrough. This object is carried out by the construction set forth below and shown in the drawings wherein—

Figure 1 is a front elevation of this sign, drawn in true perspective; Fig. 2 is a vertical longitudinal section on the line 2—2 of Fig. 3; Fig. 3 is a horizontal fragmentary 30 section on the line 3—3 of Fig. 2; Fig. 4 is a fragmentary section on the line 4—4 of Fig. 3; Fig. 5 is a perspective detail of one of the spacers complete; and Fig. 6 is a cross section of such spacer.

While our invention is capable of use in a number of ways, we have shown it and will herein describe it as applied to a sign of that type known as illuminated lamp boxes. In the present case the box B has 40 closed top and bottom and end walls, and what might be called its front face made up of panels preferably of glass which may be clear as shown at C, partly clear or colored as shown at O, or lettered or numbered as shown at L, and which will be hereinafter referred to by the word "panel" because although they are preferably of glass they might be of other material. What 45 might be called the back of the box B is in the present instance made removable so that access to its interior can be had, and the back is shown herein as comprising top and bottom flanges F which pass inside the top and bottom walls of the box B and a body 50 which is open except for the spacers and

panels like those on the front of the box and therefore need not be described. Any suitable fastening means may be employed for holding the back within the box, and these need not be elaborated. The drawings also 60 show an electric lamp socket S from which wires W lead through one wall of the box to a proper source of electricity, and in this socket may be placed a bulb so that the lettered panels can be illuminated when desired.

Coming now to the details of the present invention, the open front of the box (and the same may be said of the open back) is surrounded by a frame consisting of a flange 1 70 depending from the top wall of the box, a flange 2 rising from its bottom wall, and two other flanges 3 projecting from its end walls—all said flanges standing in a common plane across the face of the box. Overlying and spaced slightly from the top and bottom flanges 1 and 2 are strips 4 which are secured at their upper and lower edges respectively to these flanges or the respective walls of the box, and which are spaced 75 slightly from said flanges; and these strips are soldered at their ends to the end flanges 3 at the points 5, rather than being open as usual in structures of this kind.

The panels C, O, or L are disposed in upright position within the box between the top and bottom walls (or between the in-turned flanges F of the back of the box) and are held against the inside of the flanges 1 and 2 by means of L-shaped strips 6 90 which are preferably of metal and rather small—so small in fact, that the vertical leaf of the strip is hidden behind the flange and the latter forms the border for the letter which occurs on the panel if it have one. The top leaf of the uppermost strip 6 underlies the top of the box body, and the lower horizontal leaf of the lower strip overlies the bottom of the box body. Within the latter are secured lugs 8 having threaded apertures therethrough whereby they become in effect nuts, the same being disposed so far in rear of the flanges 1 and 2 that the horizontal leaves of the L-shaped strips 6 95 may be readily passed between said flanges and nuts, and through the latter pass screws 9 whose tips bear against the vertical leaves of said strips and press them against the rear of the panels, while the panels are in turn pressed against the inner sides of the 100

110

flanges 1 and 2. To remove a panel when thus locked into the box body (or its back) it is only necessary to loosen the screws 9 within the nuts 8 and remove one of the strips 6, or at most loosen or remove both of the strips. Then the panel in question can be pushed to the rear within the box and slipped past its fellow on one side and taken out of place; and if this device be a lettered sign, this panel can be replaced by another bearing another letter or number. For separating these panels we also make use of a T-shaped spacer best shown in detail in Fig. 5. This is a strip of metal comprising a flat head 10 whose edges are turned under and carried inward until they nearly meet, and two other strips bent at right angles and having their alined leaves clamped in the head and their other leaves carried away from said head at right angles thereto into a web 11, the latter being cut off at its extremities 12 so that it is shorter than the head 10 and of a length corresponding with the distance between the inner edges of the flanges 1 and 2. Beyond this web the head projects slightly as shown, and its ends are intended to be slidably engaged with the channels formed by strips 4. These upright members or spacers are put in place with their ends engaged with the members as just described, before the panels are applied, and in the finished sign they will space the panels with lines which appear opaque to the eye if the panels themselves are translucent. Having placed or arranged the panels and their spacers as will now be understood, the L-shaped strips 6 are applied last, and the screws 9 tightened up to hold them in position. Their upright leaves are hidden behind the flanges 1 and 2 as stated above, and therefore the upright webs 11 of the spacers do not come in contact with any part of the strips within the box, and there is no interference of members. If the box be illuminated by means of a bulb placed in the socket S it becomes an illuminated sign; but we do not

wish to be limited to this feature as it is quite obvious that the means for mounting these panes or panels could be employed in other constructions and connections without departing from the principle of our invention. 55

What is claimed as new is:

1. The combination with a box having an open side, and top and bottom and end flanges along the said side standing in a common plane, and strips overlying the top and bottom flanges and secured at their edges and ends thereto; of panels within the box with their upper and lower edges in rear of said flanges, means for holding them removably in contact with the same, and spacers of T-shaped cross section having their webs of a length to stand between contiguous edges of the panels and between the inner edges of the top and bottom flanges and their heads of greater length so that they rest outside said flanges and inside said strips. 65 70

2. The combination with a box having an open side, top and bottom flanges along the same, panels within the box having their upper and lower ends in rear of said flanges, means within the box for pressing them into contact with the flanges; of upright spacers of T-shaped cross section, the webs of said spacers extending between said flanges and between adjacent panels and the heads of said spacers covering the edges of adjacent panels and extending beyond said webs at the upper and lower ends thereof to overlie said top and bottom flanges, and means for holding the ends of said heads against the outer faces of the flanges. 75 80 85

In testimony whereof we have hereunto set our hands in presence of two subscribing witnesses.

GEORGE H. REITH,
HARRY F. ANDERSON.
